CARBURETER.

1,099,293.

Specification of Letters Patent.

Patented June 9, 1914.

Application filed January 26, 1909, Serial No. 474,276. Renewed April 18, 1914. Serial No. 832,986.

To all whom it may concern:

Be it known that we, JOHN S. GOLDBERG and HARRY C. TILLOTSON, citizens of the United States, residing at Chicago, in the county of Cook and State of Illinois, have invented a new and useful Improvement in Carbureters, of which the following is a specification.

Our invention relates to carbureters, particularly to carbureters for supplying automobile engines, and the object of our invention is to provide improved construction, which will increase the efficiency of operation, particularly of the mechanism for controlling the oil and air supply and proportionment.

Our invention will be more clearly understood by reference to the accompanying drawing, which is a longitudinal sectional view.

The carbureter frame is an integral casting, comprising the body part 1, from the lower end of which extends the shelf 2 for supporting the float chamber and fuel valve mechanism parts. Extending from the top of the body part at the side opposite from the shelf 2 is the frame 3, forming an auxiliary air inlet chamber 4 and serving to support the various automatic valve mechanism parts. The body part comprises the annular base 5, from which extends the outer cylindrical shell 6 and an inner shell 7, which form between them a heating jacket 8. Across the frame 5 is the bridge section 9, which supports a sleeve 10 which extends axially with reference to the base 5 and the shell 7. The greater part of the sleeve 10 is hollow and provides a chamber 11, the upper end of the sleeve having a threaded axial opening 12, in which is threaded a nozzle frame 13, this nozzle frame being inserted through the lower end of the sleeve and secured in the threaded opening 12 by some suitable instrument engaging with the slotted head 14. The lower end of chamber 11 is closed by a threaded plug 15, as shown. A passageway 16 connects chamber 11 with the fuel reservoir 17.

The lower section of the shell 7 is of the same inner diameter as that of the annular base part 5, while the intermediate zone 18 of the shell 7 converges conically upwardly so that the imaginary apex of the inner surface of said zone will coincide with the out-

let of the nozzle frame. The upper section 55 or zone 19 of the shell 7 diverges toward and meets the upper end of the outer shell 6. We thus have passageway 20 through the carbureter, whose lower zone is cylindrical, whose intermediary zone is conically 60 convergent and whose upper zone is divergent, and the nozzle end lies in the apex of the intermediary conical section. The lower end of the passageway is open to atmosphere, and air can therefore enter and 65 flow upwardly through the passageway, and this air is deflected by the conical walls of the intermediary zone and its energy directed across the outlet of the nozzle to extract oil therefrom, and the diverging zone part 70 will cause the air and oil to become thoroughly mixed to form a suitable mixture for the engine to be supplied. The sleeve 10 is also threaded externally to receive a sleeve 21, which carries a cup-shaped annular 75 flange 22. This cup-shaped flange in the first place acts as a valve to control the flow of air into the passageway 20, the adjustment being effected by rotating the flange about the sleeve 10 to increase or decrease 80 the passage area between said flange and the lower end of the base 5. This cup-shaped flange also acts as the priming receptacle and its diameter is greater than that of the flange projection 23 at the lower end of the 85 base 5 forming the entrance to the passageway 20. When oil is fed to the flange for priming purposes its level will be above the lower end of the flange 23, and when the engine is started air will be drawn over the 90 outer edge of the flange and must pass through the oil within the cup in order to pass by the flange 23 to reach passageway 20. The incoming air is therefore thoroughly saturated with oil and a very rich starting 95 mixture is assured. The flange is locked in any adjusted position by means of a plunger 24 engaging in locking grooves 25 formed in the sleeve 21, the plunger being carried in a barrel 26 screw-threading through the base 100 part 5, a spring 27 within the barrel pressing against the plunger and tending to hold it in locking engagement with the sleeve 21.

The frame section 28 above the walls 6 and 7 forms a mixing compartment 29, 105 which communicates with the upper end of passageway 20 and with the inner end of inlet compartment 4. The upper end of

frame 28 has a flange 30, by means of which connection may be made with the engine to be supplied. A shaft 31 extending diametrically through the frame 28 carries a disk 5 valve 32 operable to control the flow of fuel from the carburetor to the engine to be supplied.

The shelf 2 supports the cylindrical glass shell 33, covered by a cap 34, the base, shell 10 and cap forming the oil receptacle 17. The flange 35 extends downwardly from the shelf 2 and supports a fuel inlet frame 36, which is held in place by the coupling flange 37, threading on the flange 35. The shelf 2 15 also supports a valve disk 38, which is held in place by means of a nut 39 engaging the lug 40 extending from the disk. The lug 40 has the axial passageway 41, whose lower end communicates with the interior of frame 36 and whose upper edges are beveled to 20 form a valve seat 42. Extending upwardly from the shelf 2, concentric with the passageway 41, is a sleeve 43, through which passes a valve stem 44. In the lower end of 25 this stem is a pocket 45 for receiving the spindle valve stem 46, this valve stem being held in place by a pivot pin 47, as shown. The valve point 48 is adapted for engaging the valve seat 42 to open and close the passageway 41 and to control the flow of oil 30 therethrough from the inlet frame 36 to the oil chamber 17. The lower end of the sleeve 43 has diametrically opposite slots 49, 50, through which extend the points 51 and 52 35 of foot-shaped levers 53 and 54, these levers being pivoted at 55 and 56 between the walls adjacent the slots 49, 50. Encircling the sleeve 43 is an annular float frame 57, slideable longitudinally along said sleeve. The 40 upper end of sleeve 43 is threaded and receives at its end the cap nut 58, a spring 59 encircling the valve stem and abutting against the head of this cap nut and a ledge 60 formed on the valve stem 44, the tendency 45 of this spring being to force the valve stem downwardly and to cause closure of the passageway 41 by the valve point 48. The float frame engages the outer ends 61, 62 of the levers 53, 54, and when the oil in the reservoir reaches a certain low level or the reservoir 50 is empty, as shown in the drawings, the heels 63, 64 of these levers will engage the disk 38. Under such conditions the weight of the float frame is sufficient to hold the 55 levers against the disk 38, so that the points 51, 52 which engage the lower end of the valve stem 44 will raise this valve stem against the force of spring 59 to thereby raise the valve point 48 and to open the passageway 41. In service, the frame 36 is connected with a source of oil supply and the oil will flow upwardly through the open passageway 41 and into the reservoir 17. When 60 a certain level is reached the buoyant effect 65 of the oil will decrease the pressure of the

float frame against the levers, and the weight of the valve stem, together with the pressure of the spring 59, will gradually overcome the effects of the float frame and the valve will gradually close the passageway 41 as the oil reaches the predetermined level. As soon, however, as the engine is set in operation, oil is withdrawn from the reservoir and the float frame again becomes effective to cause the opening of the fuel valve, and thus the fuel valve is automatically moved toward opening or closing position to control the inflow of oil and to maintain the oil at a predetermined level within the reservoir. The upper end of the valve stem terminates in a head 65, which enables the valve stem to be actuated manually, this being desired for starting purposes, while the valve stem is raised and the reservoir quickly filled to a level above the nozzle outlet, the nozzle overflowing and the oil filling the cup frame 22. The cover 34 has a central neck part 66, which is threaded to engage the sleeve 43 and the outer periphery 67 is preferably knurled. With this arrangement great leverage is provided upon the rotation of the cover, and the cover with but very little force and without any special tools can be actuated to firmly clamp between it and the shelf 2 the cylindrical shell 33 to 95 thus form an oil-tight reservoir. The shell 33 is preferably of glass, so that all the valve parts within the reservoir are at all times visible, and washers 68 of leather or other suitable material may be inserted between the shell and the adjacent metallic parts. Encircling the neck 66 is a collar 69, from which extends a vertical arm 70, the collar being held in place by a screw 71, passing through the arm and with its point engaging 100 in the groove 72 surrounding the neck 66, the arm being thereby adapted to be rotated to any position about the neck. At the upper end of the arm is pivoted a bell crank lever 73, whose one arm 74 is adapted for engagement under the head 65 and whose other arm 75 may be connected with suitable lever mechanism which may be suitably near the operator of an automobile, so that the carburetor can be adjusted for starting purposes from the operator's seat. A spring 76 normally holds the lever away from the head 65 and a spring plunger 77 cooperates with slots 78 cut in the cap nut 58 to lock said cap nut in any adjusted position. 115

On the top of frame 3 is supported the valve frame 79, which has passageways 80 through which the valve chamber 81 may communicate to the atmosphere. The lower edge of the valve frame is beveled to form a 125 valve seat 82 with which a disk valve 83 cooperates. The valve disk hub 84 is secured to a valve stem 85, which passes axially through the hub 111 supported from the valve frame 79, the lower part of the valve 130

stem passing axially through a sleeve 86 extending downwardly from the lower wall of the frame 3. The sleeve 86 has internal threads at its lower end and receives an abutment plug 87 through which plug also the lower end of the valve stem 85 passes. A spring 88 encircles the valve stem and abuts at its upper end against the valve disk 83 and at its lower end against the plug 87, 5 this spring tending to hold the valve disk 83 against its seat 82, the force of the spring being adjustable by longitudinal movement of the plug 87. When the engine begins its operation sufficient air will be admitted into 10 passageway 20 by the frame 22 and this air rushing past the nozzle end will suck up oil, and the oil and air becoming mixed upon the passage through the diverging zone and through the mixing chamber are delivered 15 to the engine. As the engine increases in speed and its suction becomes stronger, more oil and more air are necessary. The primary air supply through the passageway 20 becomes insufficient and valve 83 will be 20 opened automatically by the suction and air will flow through passageways 80, around the valve 83, and through the chamber 4 into the mixing chamber, this additional supply of air being thus controlled automatically 25 by the valve 83 and the operation of said valve being controlled primarily by the spring 88. As the speed, and therefore the suction, still increases, the nozzle 13 will no longer be able to supply sufficient oil, and 30 unless provision is made for further oil supply the valve 83 will be opened to a greater extent by the increased suction and too much air will be drawn in and the mixture will not be properly proportioned. 35 One of the main objects of our invention is to provide for additional fuel supply to the mixing chamber, which additional supply is entirely automatically controlled by the automatic air inlet valve. The additional oil supply means is in the form of a 40 second nozzle 89, which is always above the level of the oil in the reservoir and which projects into the passageway 4 to be in the path of air flow controlled by the valve 83. 45 This independent nozzle 89 is thus subject to the aspirating effect of the air entering through the auxiliary air inlet, but is not so subject to the flow of air through the main air inlet, and we thus provide an effective 50 arrangement for substantial coöperation between the auxiliary fuel and the auxiliary air. The response of the auxiliary fuel is delayed with the delay in the response of the auxiliary air valve until the greater suc- 55 tions are attained and this delay may be made more definite by disposing the second nozzle at a higher level than the first nozzle. After the response of both auxiliary air and fuel, the air valve being properly retarded 60 as above described, the coöperation resides in the fact that the issue from the nozzle 89 varies with the aspiration, and the aspiration is determined by the opening of the air valve due to suction. Until about the time of response of the auxiliary air valve, the 65 fuel nozzle 89 gives forth no fuel. We also provide an additional feature in the way of bleeding means for positively preventing even the slightest issue (which may ordinarily be negligible) from the fuel nozzle 89 before the auxiliary air valve is opened. This feature includes means for adjustment by which the bleeder may be brought into 70 and out of action and by means of which, when the bleeder is in action, the response of fuel from the nozzle 89 may be definitely and adjustably delayed even somewhat beyond the opening of the auxiliary air valve. As best shown in Fig. 3, the carburetor frame has the enlargement 90, in which is formed 75 the passageway 91, through which the nozzle 89 is inserted, the nozzle being threaded into position as shown. After insertion of the nozzle the end of the passageway 91 is closed by means of a plug 92. The enlargement 90 forms a horizontal shelf 93 from which extends a passageway 94, whose lower end communicates with the passageway 91 connecting with the nozzle. The upper end of this passageway communicates with 80 atmosphere and the adjacent edges are beveled to form a valve seat 95. A duct 96 extends through the base 5 and through the wall 6 and connects with the passageway 91 and with the compartment 11, the nozzle 89 85 being therefore connected with the oil receptacle. Carried by the valve 83 and concentric with the vertical passageway 94 is a downward sleeve extension 97, which sleeve is internally threaded to receive the threaded lower end of a tube or barrel 98. Extending 90 through this barrel is a valve stem 99, whose lower valve end 100 coöperates with the valve seat 95. A spring 101 within the barrel abuts against the shoulder 102 on the 105 valve stem and a shoulder 103 near the top of the barrel, this spring tending to force the valve spindle downwardly, the desired movement of the valve stem being, however, limited by the head 103 at the upper end of the valve stem, which head engages the upper end of barrel 98. By the rotation of the barrel 98 the adjustment of the valve end with reference to the valve seat 95 can be 110 regulated. A locking plunger 104 extends from pocket 105 and by means of spring 106 is held in locking engagement in locking slots 107 provided in the outer face of the barrel 98. 115 The adjustment illustrated is such that 120 the valve end 100 will be supported away from the seat 95 by the head on the stem 99 when the valve 83 is closed and therefore the nozzle 89 will be connected directly with atmosphere through passageway 94 and the 125 130

suction of the engine will have no effect on the oil within passageway 96. In other words, suction on the oil in the passageway 96 is then controlled entirely by the atmospheric inlet 94. Therefore in the beginning of the operation of the engine, when valve 83 is closed, nozzle 89 will be ineffective and only nozzle 13 will supply oil. As the engine increases in speed and suction, additional air flow is provided for by valve 83, and this valve upon opening will carry the valve point 100 toward the seat 95, and as soon as the condition is reached where nozzle 13 will be inadequate for the oil supply and the suction becomes such that the valve 83 will be opened wider, the valve point 100 will be carried against seat 95 and the atmosphere passageway 94 closed and the suction can then become effective to draw oil from the nozzle 89, and the oil from this nozzle is carried into the mixing chamber with the air entering through passageway 4. Of course, as soon as the valve 83 moves downwardly the entrance to passageway 94 will be decreased and the suction effect on the nozzle will increase so that oil will begin to rise into the passageway 91 and nozzle 89, but oil will not be delivered from the nozzle until such proper time when more oil is required by the engine. As soon as the passageway 94 is closed by the valve end 100 the valve 83 can open to any further extent depending upon the suction, the spring 103 firmly holding the valve end 100 against the seat 95. As soon as the speed of the engine again decreases valve 83 will close, whereupon the atmosphere passageway 94 again opens and the nozzle 89 ceases to supply oil. With this arrangement the additional oil supply is definitely controlled entirely automatically by the automatic air valve, the operation being such that the valve 83 will supply additional air as the requirements vary and the valve 100 is automatically controlled by the movement of the valve 83 to cause additional oil supply in proportion to the air supply controlled by the valve 83. The supply and the proper proportioning of air and oil are thus entirely automatically controlled by the various nozzle valve mechanisms to meet all the varying conditions of operation of the engine to which the carbureter is connected.

The spring 88 will be sufficient during the ordinary operation of an engine to properly control the valve 83, but its control of the valve will not be accurate after the engine reaches a certain speed; the suction becoming greatly increased will not be sufficiently resisted by the spring 88 and too much air would enter, the spring 88 being comparatively light in order to afford proper regulation under ordinary conditions of operation. As a means for assisting the spring 88 to give proper regulation after a certain in-

crease of speed, a secondary spring 108 is provided, this spring encircling the valve stem 85 between an end nut 109 secured to the stem and the cap nut 110 engaging the neck 111 extending from the frame 79. As shown, the adjustment is such that the upper end of the secondary spring is away from the nut 109 when the carbureter is at rest, but during operation of the engine the valve 83 moves downwardly and when the critical point is reached the nut 109 will engage with the secondary spring and the secondary spring then becomes effective to assist the spring 88 in controlling the operation of valve 83 and to prevent the admission of too much air. The suction effect on the valve 83 under such high speed conditions is considerable and the secondary spring is therefore made comparatively heavy. The time at which the secondary spring comes into operative service is adjustable by means of the cap nut 110, which is carried in adjusted position by the lock plunger 112 carried in the barrel 113, supported from frame 79, the spring 114 in such barrel tending to force the plunger into locking engagement with the locking slots 115 cut in the cap nut. The spring 88 is also readily adjustable upon the rotation of the sleeve 116 connected with the outer end of the plug 87 and encircling the extension 86, a spring plunger 117 suitably supported tending to lock the plug 87 in adjusted position by engaging in locking slots 118.

All the parts of the carbureter are of very simple but durable construction and the various adjustable parts can be easily and quickly manipulated without the use of special tools. No adjustments are necessary after a primary setting of the carbureter parts in connection with the engine which the carbureter is to supply, the parts after such setting being mutually controlled and automatically regulated so that for all conditions of operation of the engine the explosive mixture will be the most efficient.

We do not wish to be limited to the precise constructions and arrangements as illustrated, as changes can readily be made without departing from the scope of our invention.

The claims we make are the following:

1. In a carbureter, the combination of a carbureting chamber having an air inlet, a valve controlling said inlet, a nozzle for supplying oil to the carbureting chamber, an atmosphere inlet to said nozzle, and means automatically controlled by said valve for adjusting said atmosphere inlet to control the oil flow from the nozzle.

2. In a carbureter, the combination of a carbureting chamber, an oil nozzle, an oil reservoir connected with said oil nozzle, an atmosphere inlet to said nozzle, and a valve operating according to and by the engine

- suction for automatically controlling the inlet to allow the extraction of oil from said nozzle.
3. In a carbureter, the combination of a carbureting chamber having an air inlet, a nozzle for supplying oil to the carbureting chamber, an oil reservoir connected with the nozzle outlet, an atmosphere inlet to said nozzle for rendering the generation of suction within the carbureter chamber more or less ineffective to extract the oil, and means controlled by the air flow through the inlet for controlling said atmosphere inlet to allow extraction of oil from said nozzle.
4. In a carbureter, the combination of a carbureting chamber, a nozzle for supplying oil to the carbureting chamber, an oil reservoir connected with the nozzle through a passageway, said carbureting chamber being connected with the reservoir by way of said nozzle and passageway, said nozzle outlet being above the level of oil in said reservoir, an atmosphere inlet to said passageway, said inlet rendering the creation of suction within the carbureting chamber ineffective to extract oil, and valve mechanism for automatically controlling said inlet to allow extraction of oil from said nozzle.
5. In a carbureter, the combination of a carbureting chamber, a nozzle for supplying oil to the carbureting chamber, an oil reservoir connected with the nozzle through a passageway, said carbureting chamber being connected with the reservoir by way of said nozzle and said passageway, said nozzle outlet being above the level of oil in said reservoir, an atmosphere inlet to said passageway, said passageway inlet rendering creation of suction within the carbureting chamber more or less effective to extract oil, an air inlet to the carbureting chamber, a valve automatically controlling said air inlet, and valve mechanism actuated by said valve to control the atmosphere inlet to allow extraction of oil from said nozzle.
6. In a carbureter, the combination of a carbureting chamber, a nozzle for supplying oil to the carbureting chamber, an oil reservoir connected with the nozzle through a passageway, said carbureting chamber being connected with the reservoir by way of said nozzle and passageway, said nozzle outlet being above the level of oil in said reservoir, an atmosphere inlet to said passageway, said atmosphere inlet rendering the creation of suction within the carbureting chamber more or less ineffective to extract oil, an air inlet to the carbureting chamber, a valve automatically controlling said air inlet, and valve mechanism carried by said inlet valve for controlling said atmosphere inlet upon opening of the inlet valve to allow extraction of oil from said nozzle by the suction within the carbureting chamber.
7. In a carbureter, the combination of a carbureting chamber, a main nozzle for supplying oil to the carbureting chamber, an auxiliary nozzle for supplying oil to the carbureting chamber, an oil reservoir connected with said nozzles, an air inlet, an atmosphere inlet to the auxiliary nozzle effective when the air valve is closed to render the auxiliary nozzle inoperative, and means automatically controlled by the air valve for adjusting the atmosphere inlet to render the auxiliary nozzle operative when said air valve has been opened a predetermined amount.
8. In a carbureter, the combination of a carbureting chamber, a main nozzle for supplying oil to the carbureting chamber, said main nozzle being always operative, an auxiliary nozzle, an air inlet to the carbureting chamber, a second air inlet associated with said auxiliary nozzle, an automatic valve controlling said second inlet, and means for rendering the auxiliary nozzle inoperative during a predetermined range of operation of the air valve and for causing the auxiliary nozzle to become effective at a certain point in the operation of said air valve.
9. In a carbureter, the combination of a carbureting chamber, a main nozzle for supplying oil to the carbureting chamber and always operative, an auxiliary nozzle for assisting in supplying oil to the carbureting chamber, an air inlet to the carbureting chamber, a second air inlet associated with said auxiliary nozzle, an automatic air valve controlling said second inlet, and means for rendering the auxiliary nozzle inoperative during a predetermined range of operation of the automatic valve, said means being controlled by said valve to coöperate with said first means to render the auxiliary nozzle operative when a certain point in the operation of said automatic valve is reached.
10. In a carbureter, the combination of a common carbureting chamber connected with an engine adapted to be supplied, an oil reservoir, a main oil inlet and an auxiliary oil inlet to said carbureting chamber, both said inlets opening permanently into the carbureting chamber and being connected with the oil reservoir, an air inlet, a valve controlling said air inlet, means for preventing the withdrawal of oil through the auxiliary inlet by suction when said valve is closed, and means automatically controlled upon opening of the valve to render said first means ineffective thus to allow oil flow through said auxiliary inlet.
11. In a carbureter, the combination of a carbureting chamber, an oil reservoir, an oil inlet communicating with the carbureting chamber and with the oil reservoir, an air inlet to the carbureting chamber, a valve controlling said inlet, said carbureter being

adapted for connection with an engine so that suction will be created in the carbureting chamber upon operation of the engine, means for destroying the suction effect at the oil inlet when the valve is closed and when it is open to a certain extent, and means for automatically allowing the suction to become effective to extract oil through the inlet when said valve opens beyond said extent.

10 extent.

12. In a carbureter, the combination of a suction chamber, an inlet to the suction chamber, a valve controlling said inlet, a fuel passageway permanently connecting a source of fuel with the suction chamber, an auxiliary air inlet to the suction chamber by way of part of said passageway for nullifying or decreasing the suction effect on the fuel in the passageway, said auxiliary air inlet being controlled by the valve to adjust the suction effect on the oil in the passageway.

13. In a carbureter, the combination of a carbureting chamber, a fuel passageway for feeding fuel to the carbureting chamber from a fuel source, an atmosphere inlet to said passageway for preventing withdrawal of fuel from said passageway by suction within the carbureting chamber, and means for automatically controlling the inlet according to and by means of the engine suction to allow the extraction of fuel from said passageway.

14. In a carbureter for internal combustion engines, a carbureting chamber having a mixture outlet at the top and having a main air inlet and passageway leading thereto from the bottom, a throttle valve controlling said mixture outlet, a liquid fuel reservoir, a main fuel nozzle disposed in

40 said passageway and connected with said reservoir, means for maintaining a constant level of liquid fuel in said reservoir, the feed outlet of said main fuel nozzle being a short distance above said fuel level, an auxiliary
45 air inlet and passageway leading into said carbureting chamber at a considerable distance above said fuel level but below said throttle, a suction-operated valve controlling said auxiliary air inlet responding
50 only on the higher suctions, two springs arranged to resist the opening of said valve, one of said springs being always in action and the other being a stronger spring and coming into play after the valve
55 has been opened a predetermined amount and an independent auxiliary fuel nozzle leading from said reservoir into said auxiliary passageway and having its feed outlet at a considerably greater distance above said
60 fuel level than said main feed outlet, both of said fuel nozzles thus permanently communicating with the same carbureting chamber and being thus subject to variations in pressure therein, the lower nozzle being active at all suctions and the response of the

upper nozzle being delayed due to the height to which the liquid fuel must be raised before it reaches the upper feed outlet until the auxiliary air valve opens to control the aspirating effect on said auxiliary nozzle.

15. In a carburetor for internal combustion engines, a carbureting chamber having a mixture outlet at the top and having a main air inlet and passageway leading thereto from the bottom, a throttle valve controlling said mixture outlet, a liquid fuel reservoir, a main fuel nozzle disposed in said passageway and connected with said reservoir, means for maintaining a constant level of liquid fuel in said reservoir, the feed outlet of said main fuel nozzle being a short distance above said fuel level, an auxiliary air inlet and passageway leading into said carbureting chamber at the side at a considerable distance above said fuel level but below said throttle, a valve controlling said auxiliary air inlet, and a permanently open independent auxiliary fuel nozzle leading from said reservoir into said auxiliary passageway so as to be directly subject to the aspirating effect of the air entering through said auxiliary air inlet but not so subject to the air entering through said main air inlet, and having its feed outlet at a considerably greater distance above said fuel level than said main feed outlet, both of said fuel nozzles thus permanently communicating with the same carbureting chamber and being thus subject to variations in pressure therein, the lower nozzle being active at all suction and the response of the upper nozzle being delayed due to the height to which the liquid fuel must be raised before it reaches the upper feed outlet. 75 80 85 90 95 100

16. In a carbureter for internal combustion engines, a carbureting chamber having a mixture outlet at the top and having a main air inlet and passageway leading thereto from the bottom, a throttle valve controlling said mixture outlet, a liquid fuel reservoir, a main fuel nozzle disposed in said passageway and connected with said reservoir, means for maintaining a constant level of liquid fuel in said reservoir, the feed outlet of said main fuel nozzle being a short distance above said fuel level, an auxiliary air inlet and passageway leading into said carbureting chamber at the side at a considerable distance above said fuel level but below said throttle, a suction-operated valve controlling said auxiliary air inlet responding only on the higher suction, and a permanently open independent auxiliary fuel nozzle leading from said reservoir into said auxiliary passageway so as to be directly subject to the aspirating effect of the air entering through said auxiliary air inlet but not so subject to the air entering through said main air inlet and having its feed outlet at a considerably greater distance above 130

said fuel level than said main feed outlet, both of said fuel nozzles thus permanently communicating with the same carbureting chamber and being thus subject to variations in pressure therein, the lower nozzle being active at all suctions and the response of the upper nozzle being delayed due to the height to which the liquid fuel must be raised before it reaches the upper feed outlet until the auxiliary air valve opens to control the aspirating effect on said auxiliary nozzle.

17. In a carbureter for internal combustion engines, a carbureting chamber having a mixture outlet at the top and having a main air inlet and passageway leading thereto from the bottom, a throttle valve controlling said mixture outlet, a liquid fuel reservoir, a main fuel nozzle disposed in said passageway and connected with said reservoir, means for maintaining a constant level of liquid fuel in said reservoir, the feed outlet of said main fuel nozzle being a short distance above said fuel level, an auxiliary air inlet and passageway leading into said carbureting chamber at a considerable distance above said fuel level but below said throttle, a suction-operated valve controlling said auxiliary air inlet responding only on the higher suctions, two springs arranged to resist the opening of said valve, one of said springs being always in action and the other being a stronger spring and coming into play after the valve has been opened a predetermined amount, independently adjustable means for determining the tension of the first spring and for determining the point where the second spring comes into action, and an independent auxiliary fuel nozzle leading from said reservoir into said auxiliary passageway and having its feed outlet at a considerably greater distance above said fuel level than said main feed outlet, both of said fuel nozzles thus permanently communicating with the same carbureting chamber and being thus subject to variations in pressure therein, the lower nozzle being active at all suctions and the response of the upper nozzle being delayed due to the height to which the liquid fuel must be raised before it reaches the upper feed outlet until the auxiliary air valve opens to control the aspirating effect on said auxiliary nozzle.

18. In a carbureter for internal combustion engines, a carbureting chamber having a throttle-controlled mixture outlet and two air inlets below the throttle, one of said air inlets being permanently open, a normally closed suction-controlled valve for the other air inlet, and a fuel nozzle for each air inlet, both fuel nozzles being in permanent open communication with the carbureting chamber but each fuel nozzle being disposed in the pathway of the air entering its respective air inlet so as to be directly subject to the

aspirating effect of the air entering its respective air inlet but not so subject to the air entering through the other air inlet.

19. In a carbureter for internal combustion engines, a carbureting chamber having a throttle controlled mixture outlet and two air inlets below the throttle, one of said air inlets being permanently open, a normally-closed suction-controlled valve for the other air inlet, and a fuel nozzle for each air inlet, both fuel nozzles being in permanent open communication with the carbureting chamber but each fuel nozzle being disposed in the pathway of the air entering its respective air inlet so as to be directly subject to the aspirating effect of the air entering its respective air inlet but not so subject to the air entering through the other air inlet, and means for resisting the opening of said suction-controlled valve so that it will respond only on the higher suctions.

20. In an engine carbureter, a carbureting chamber, a fuel reservoir, a main air inlet, a main fuel nozzle connected with said reservoir and associated with said main air inlet, an independent permanently open auxiliary fuel nozzle connected with said reservoir and having its feed outlet at a point higher than the feed outlet of the main nozzle, a throttle controlling the mixture outlet, an auxiliary air inlet, a suction-controlled valve controlling said auxiliary air inlet, a plurality of springs arranged to resist the opening movement of the valve, said springs coming into play successively and means for adjusting the tension of the first spring and determining the point at which the second spring comes into play.

21. In a carbureter for internal combustion engines, a carbureting chamber having a mixture outlet and two air inlets, one of said air inlets being permanently open, a normally closed suction-controlled valve for the other air inlet, a fuel nozzle for each air inlet, each fuel nozzle being disposed in the pathway of the air entering its respective air inlet so as to be directly subject to the aspirating effect of the air entering its respective air inlet but not so subject to the air entering the other air inlet, and two springs arranged to resist the opening movement of said valve, one of said springs being always in action and the other being stronger than the first and coming into play only after the valve has opened a predetermined amount.

22. In combination, a double carbureter, each element comprising an air inlet and a fuel inlet, each fuel inlet being disposed in the pathway of the air entering its respective air inlet so as to be directly subject to the aspirating effect of the air entering its respective air inlet but not so subject to the air entering through the other air inlet, the air inlet of one carbureting element being per-

manently open, a suction-controlled valve controlling the air inlet of the other carbureting element, and a plurality of springs arranged to resist the opening movement of said valve, said springs being arranged to come into play successively.

23. In a carbureter for internal combustion engines, a carbureting chamber having a throttle-controlled mixture outlet, permanent air inlet means of constant size leading into said carbureting chamber, valve-controlled air inlet means leading into said carbureting chamber, and a fuel nozzle for each air inlet means, both fuel nozzles being in permanent communication with the carbureting chamber but each fuel nozzle being disposed in the pathway of the air entering its respective air inlet so as to be directly subject to the aspirating effect of the air entering its respective air inlet but not so subject to the air entering through the other air inlet.

In witness whereof, we hereunto subscribe our names, this 20th day of January, 1909.

JOHN S. GOLDBERG.
HARRY C. TILLOTSON.

Witnesses for both:

CHARLES J. SCHMIDT,
GEORGE E. HIGHAM.
